UNITED STATES PATENT OFFICE.

COLUMBUS K. LASSITER AND JULIUS KINDEEVATER, OF NEW YORK, N. Y.; ANNIE FRANCES LASSITER ADMINISTRATOR OF SAID COLUMBUS K. LASSITER, DECEASED.

SUPERHEATER HEADER.

Application filed April 5, 1921. Serial No. 458,793.

To all whom it may concern:

Be it known that we, COLUMBUS K. LASSITER and JULIUS KINDEEVATER, citizens of the United States, residing at New York, county of New York, and State of New York, have invented new and useful Improvements in Superheater Headers, of which the following is a specification.

This invention relates to headers or steam collectors for superheaters and particularly locomotive superheaters of that type wherein the header or collector is provided with saturated steam and superheated steam chambers or compartments communicating respectively with the dry pipe and steam chest supply pipes and with the receiving and delivery ends of superheater pipes or units arranged in flues (fire tubes) so as to be heated by the gases of combustion from the boiler.

One object of the invention is to provide a header having a novel construction and arrangement of the saturated and superheated steam compartments whereby the conducting capacity of the header is increased without sacrificing compactness, and with the advantage that a greater number of superheater pipes or units may be connected therewith than is possible with headers of the types heretofore in use.

A further object of the invention is to provide a header which is simple of construction, reliable and efficient in operation, capable of being easily and economically made and assembled with its cooperating parts in the locomotive, and which allows all parts to be conveniently reached for disassembly, repairs or other purposes.

A still further object of the invention is to provide a header which allows more direct and freer flow of steam, which is rigid and staunch in construction and free from structural parts liable to cause deleterious strains due to temperature differences between different portions of the header, and which also obviates liability of heat losses from heat exchange between such portions of the header.

In the accompanying drawings illustrating a preferred form of embodiment of the invention,—

Figure 1 is a partial vertical longitudinal central section through the front part of a

locomotive boiler, showing the application of the invention.

Figure 2 is a vertical transverse section thereof, the plane of section through the header being indicated by the line 2—2 of Figure 3.

Figure 3 is a top plan view of the header.

Figure 4 is a fragmentary horizontal section thereof.

Figure 5 is a section on line 5—5 of Figure 3.

Referring to the drawings, 1 designates the smokebox, 2 the front tube sheet, 3 the vertical rows of smoke tubes, 4 the superheater tubes or units, 5 the improved header or collector constructed in accordance with the present invention, and 6 one of the two steam supply pipes leading from the header to the steam chests. The superheater tubes or units are arranged as usual in vertical rows, and each tube or unit has an inlet end 7 for admission of the saturated steam thereto and an outlet end 8 for discharge of the superheated steam therefrom.

The header 5 comprises a body of generally oblong rectangular form in plan and constructed as a whole of an integral casting. It is preferably arranged, as shown, horizontally in and across the fire-box above the level of the smoke tubes and may be supported in position in any suitable manner. It is provided with any suitable number of compartments for saturated and superheated steam, according to the size of the locomotive on which it is to be employed and the number of superheater tubes or units which are to be connected therewith, at least one superheated steam compartment and one saturated steam compartment being essential. In the present instance the header is shown as having four unitary or separately formed steam compartments 9, 10, 11 and 12, the compartments 9 and 11 being saturated steam compartments and the compartments 10 and 12 superheated steam compartments. The saturated and superheated steam compartments are arranged one in advance of the other, and at the same or substantially the same horizontal level, and said saturated and superheated steam compartments alternate in arrangement with each other for proper connection and cooperation with the superheater tubes or units.

For the purpose of securing certain important advantages in simplicity of structure, ease of manufacture and operating efficiency, the several compartments 9, 10, 11 and 12 are disposed in spaced relationship and each compartment is formed complete in itself and comprises in its structural organization front and rear walls, end walls, a top wall and a bottom wall. As shown, however, the bottom walls of all the compartments comprise component parts of a bottom plate 13 which constitutes the base of the header rigidly uniting all the parts thereof and thereby providing a header of great strength and durability. It will be observed that the compartments are straight and parallel with each other throughout their lengths, and that each compartment forms a steam chamber which is continuous from end to end thereof, that is, devoid of cross partitions of any character subdividing it into separate branches or steam chambers. By constructing the compartments in this manner simplicity of design and manufacture is obtained, inasmuch as the straight and parallel relationship of the compartments permits of ease in molding or casting and ensures uniform section of metal, while the flow of steam through the compartments is freer and more direct than in prior header structures in which the compartments are sub-divided by cross walls into a plurality of chambers through which the steam circulates back and forth or more or less indirectly. Moreover, by the elimination of cross walls or partitions, the temperature and pressure strains to which the header is subjected in service are reduced to a minimum, the temperature and pressures more evenly transmitted throughout the header, and liability of warping or fracture prevented or reduced to a very large degree.

The compartments are provided in their bottom portions with openings for the connection of the ends of the superheater pipes or units therewith, and each compartment is made of a proper width or cross-sectional area with regard to its required steam capacity according to the number of rows of openings which are formed therein and aggregate number of the ends of the superheater pipes connected therewith. As shown the saturated steam compartments 9 and 11 are provided with rows of openings 14 for connection with the inlet ends 7 of the superheater pipes 4, while the superheated steam compartments 10 and 12 are provided with rows of openings 15 for the connection of the outlet ends 8 of the superheater pipes therewith. The compartments 9 and 12, as shown, are made of limited cross-sectional area or single width and provided each with a single row of openings 14 and 15, respectively, for respective connection therewith of the inlet and delivery ends of a definite number of the superheater pipes. Each of the compartments 10 and 11, on the other hand, is of twice the cross-sectional area of the compartments 9 and 12, or of double width, and each of said compartments 10 and 11 is provided with two rows of openings, the compartment 10 having two rows of openings 15 for connection with the outlet ends and the compartment 11 two rows of openings 14 for connection with the inlet ends of a definite number of the superheater pipes. The relative areas of the compartments may, however, be varied as occasion requires and according to any desired number grouping of the tubes with respect to the sets of compartments. The openings 14 and 15 extend through the bottom plate 13 in longitudinal rows along the length of the steam compartments and are also properly arranged in transverse rows throughout the several compartments, thus allowing the ends of the superheater pipes to be arranged in compact order and conveniently disposed for application, removal and repairs. It will be seen that in the use of four steam compartments 9, 10, 11 and 12, constructed and arranged as described, six openings 14 and 15, equally divided in number, are provided in each transverse row. Hence by disposing the inlet and outlet ends 7 and 8 of each tube so that one tube end lies immediately in rear of the other tube end, each transverse row of tube openings 14 and 15 will accommodate the inlet and outlet ends 7 and 8 of three superheater tubes of a vertical group or row in such manner that the inlet and outlet ends of each tube may be fitted in two adjoining openings 14-15 of a transverse row and so as to be properly connected with the alternately arranged saturated and superheated steam compartments. Such fitting of the ends 7-8 of each tube in adjoining openings 14-15 adapts the ends of each superheater unit to be held in position by a single transverse fastening, such as a clamp 16, secured in place by a bolt 17, upon the detachment of which single clamp the superheater unit is released for removal. As shown in Figure 1, the clamps 16 which secure the ends 7-8 of the three tubes connected with each transverse row of openings 14-15, may be arranged in longitudinal alinement in a transverse row or series on the underside of the header for convenience in applying or removing the sub-group of three tubes so arranged and fastened in place. Moreover, as shown in Figures 1 and 2, by disposing the tubes vertically edgewise, i. e., with their backwardly and forwardly extending limbs in superimposed relation and alternately arranging the superposed tubes of a vertical group or row in rights and lefts in the flues 3, that is, so that the ends 7-8 of one tube will lie one in rear of the other and extend

from the right hand side of the tube, while the ends 7—8 of the immediately overlying or underlying tube will similarly lie one in rear of the other and extend from the left hand side of the latter-named tube, the ends 7—8 of alternate tubes of a vertical group or row will be offset from each other so as to lie close to each other but in different parallel vertical planes. By thus arranging 10 the tubes of a main vertical group in two right and left hand subdivisions, the tubes of such subdivisions alternating in arrangement with each other, the left hand tube ends of one subdivision of a group may be 15 fitted in one transverse row of openings 14—15 in the header, while the right hand tube ends of the other subdivision of the same group will lie in such close relationship to the tube ends of the first-named subdivisions of the group that they may be 20 fitted in the next adjoining row of transverse openings 14—15 in the header. From this it will be seen that two closely related transverse rows of openings 14—15 in the 25 header will accommodate the ends of six superheater tubes, the described construction and arrangement of parts therefore allowing tubes in vertical rows or groups, of as many as six tubes to a row or group, to be 30 used in a compact manner and with a very compact form of header. Furthermore, such an arrangement of the superheater tubes permits the tubes and their receiving openings in the header to be so relatively 35 placed that the tube ends may be extended at their extremities on straight vertical lines for connection with their pairs of tube end receiving openings in the header, with a minimum degree of bending of the tube 40 ends in any direction and without the necessity of crossing the tube ends or bending them in any other than an upward direction for a fitting connection, making them easy of application and removal, and reducing 45 time, labor and expense in their application and removal. Still another advantage arising from the described construction of the header and arrangement of the tubes is that any tube in a row in rear of a tube whose 50 ends are outermost may be reached for removal or repairs upon removal of the preceding tube or tubes in the same row whose ends are outwardly beyond the ends of the tube in question and without the necessity 55 of removing any other tube in rear thereof in the same row, or of removing one or more tubes of an adjoining vertical row, as is necessary either where the tube ends are not connected to successive tube receiving 60 openings in a row of openings or where they are connected to tube receiving openings in two adjoining rows of openings. By disposing the steam compartments in the manner described spaces or passages 18 are 65 formed therebetween and the rows of holes

for the bolts 17 may be formed in the bottom plate 13 so as to communicate with these spaces or passages, allowing of the ready and convenient application and removal of the bolts as occasion requires. 70 The saturated steam compartments 9 and 11 are in communication at their top portions, and at a point centrally of their length, with an inlet conductor 19, which arches over the intervening superheated steam compartment 10, said passage 19 terminating at its rear end in an inlet neck 20 of a suitable form for connection with the dry pipe A, whereby the saturated steam flows from the steam space of the boiler to the saturated steam compartments 9 and 11 for circulation through the superheater pipes 4. The bottom wall 21 of this inlet conductor 19, which extends over the top wall of the compartment 10, is separated from the latter by an air space 22. The superheated steam compartments 10 and 12 are connected on opposite sides of the inlet conductor 19 with discharge conductors 23, having outlet ends 24 of suitable form for 80 respective connection with the steam chest supply pipes 6 leading to the steam chests at the opposite sides of the locomotive. These conductors 23 arch over the intervening 85 saturated steam compartment 11 and their bottom walls 25 are separated from the top wall of said compartment 11 by air spaces 26. It will be observed from the foregoing that the conductors 19 and 23 are cast integral with the walls of the compartments 90 with which they are connected and cooperate with the bottom plate 13 to rigidly unite all parts of the header, thus securing maximum strength and durability in the header construction. Also it will be observed that as 95 said conductors are separated by air spaces from the compartments over which they arch, undue variations of temperatures between the compartments and loss of heat 100 from the superheated steam due to heat exchange between the superheated steam and the saturated steam will be avoided or reduced to the minimum. Hence the header 105 is not liable to become warped in service or to be subjected to uneven or ununiform temperature and pressure changes liable to cause 110 fractures or other deleterious effects, and consequently a high degree of working efficiency is secured. 115 In the operation of the header, it will of course be apparent that the saturated steam from the supply pipe enters the conductor 19 and flows therefrom into the saturated steam compartments 9 and 11, thence 120 through the superheater pipes or units 4, and from said pipes or units into the superheated steam compartments out through the conductors 23 into the steam chest supply pipes 6 for delivery to the chests of the working cylinders at the opposite sides of 125 130

the locomotive. The various saturated and superheated steam compartments being straight and parallel and entirely uninterrupted throughout their lengths, it will be 5 obvious that the steam may flow easily and freely through said compartments, thus avoiding any objections incident to back pressures or resistances to the flow of the steam as fast as formed and superheated to 10 the steam chests for use. The described construction and arrangement of the saturated and superheated steam compartments provides, as hereinbefore stated, a compact form of header which will accommodate six 15 vertical rows of superheater pipes of as many as six pipes to a row as commonly arranged in the largest sized locomotives, and it will be evident that the capacity of the header may be diminished or increased by 20 using a lesser or greater number of compartments. With the construction shown, a header having a sufficient number of compartments for locomotives of even larger size and having, if required, more than six 25 superheater pipes in each vertical row may be employed without objectionably increasing the size of the header or unduly extending it forwardly within the smoke-box. In this respect a great advantage is gained 30 over ordinary headers which, whether of one-piece or two-piece formation, provide only for connection with rows of tubes limited to an arrangement of four tubes in each vertical row. A still further advantage of 35 our improved construction is that the described arrangement of the bolt holes 17 permits of the use of shorter clamping bolts, and these holes as well as the tube holes 14 and 15 may be drilled with a jig, ensuring 40 proper relation one to the other and avoiding any irregular spacing.

Having thus fully described our invention, we claim:

1. In a superheater, a header comprising 45 a unitary casting of oblong rectangular form in plan and embodying a plurality of pairs of longitudinally straight saturated and superheated steam compartments, said compartments being of unitary formation 50 and separate from and independent of connection with each other except at the base and each composed of integral top, side and end walls, the adjacent side walls of the compartments being spaced by longitudinal 55 channels extending from end to end of the header, and a base plate of unitary construction integral with said walls of the compartments and closing the bottoms thereof 60 and having portions bridging across and closing the bottoms of said channels; the portions of the base plate forming the bottom walls of the compartments being provided with an even number of longitudinal rows of tube receiving openings communicating 65 with the compartments, said openings

being also arranged in transverse rows of even number across the series of compartments, and said bridging portions of the base plate being provided with longitudinal rows of bolt receiving openings communicating with the base of said channels, said bolt receiving openings being also arranged in transverse rows alining with the transverse rows of tube receiving openings. 70

2. In a superheater, a header comprising 75 a unitary casting of oblong rectangular form in plan and embodying a plurality of longitudinally continuous and longitudinally spaced straight saturated and superheated steam compartments, said compartments 80 having their adjacent sides separated by continuous longitudinally extending channels, a base plate integral with the walls of the compartments and extending continuously across the compartments and channels 85 and closing the bottoms of said compartments and bases of the channels, the said saturated and superheated steam compartments alternating in arrangement with each other from the front to the rear of the header, the bottom walls of the compartments formed by the plate portions being provided with longitudinal rows of tube receiving openings, said rows also extending in transverse 90 rows across the series of compartments, and the bottoms of the channels formed by the plate portions being provided with longitudinal rows of bolt receiving openings alining with the transverse rows of tube receiving 95 openings, a saturated steam inlet extending from the rear in a plane parallel with the horizontal plane of the header and communicating with the tops of the saturated steam compartments, the bottom wall of said steam inlet being integral with the front side wall of the rear saturated steam compartment and rear side wall of the front saturated steam compartment and arching over and thermally insulated from the top 100 of the intervening superheated steam compartment, and superheated steam outlets having their inlet ends overlying and communicating with the tops of the superheated steam compartments, said steam outlets extending forwardly therefrom across the header, the bottom walls of said superheated steam outlets being integral with the rear side wall of the front superheated steam compartment and front side wall of the rear superheated steam compartment, and arching over and thermally insulated from the intervening saturated steam compartment. 105

3. In a superheater, a header having two 110 pairs of saturated and superheated steam compartments extending longitudinally of the header, said saturated and superheated steam compartments alternating in arrangement with each other, a saturated steam inlet extending from the rear in a plane parallel with the horizontal plane of the header 115

over the header and communicating with the tops of the saturated steam compartments, and arching over and separated from the top of the intervening superheated steam compartment, and superheated steam outlets having their inlet ends overlying and communicating with the tops of the superheated steam compartments and extending forwardly therefrom across the header, and arching over and separated from the top of the intervening saturated steam compartment.

4. In a superheater, a header having two pairs of unitary saturated and superheated steam compartments extending longitudinally of the header, said saturated and superheated steam compartments being separate from and independent of each other and alternating in arrangement with each other, the adjacent walls of said chambers being spaced apart, a saturated steam inlet extending from the rear in a plane parallel with the horizontal plane of the header and communicating with the tops of the saturated steam compartments, the bottom wall of said steam inlet being integral with the front side wall of the rear saturated steam compartment and rear side wall of the front saturated steam compartment and arching over and thermally insulated from the top of the intervening superheated steam compartment, and superheated steam outlets having their inlet ends overlying and communicating with the tops of the superheated steam compartments, said steam outlets extending forwardly therefrom across the header, the bottom walls of said superheated steam outlets being integral with the rear side wall of the front superheated steam compartment and front side wall of the rear superheated steam compartment, and arching over and thermally insulated from the intervening saturated steam compartment.

5. In a superheater, the combination of a

boiler having a vertical row of at least six superheater tube smoke flues and a group of at least six superheater tubes arranged one above the other in said flues in substantially the same vertical plane, each tube having end portions arranged one in advance of the other, the tubes of the group being disposed in two equal subdivisions, the tubes of one subdivision having their end portions extending from their left hand sides and arranged one in advance of the other in one vertical plane and the tubes of the other subdivision having their end portions extending from their right hand sides and arranged one in advance of the other in a different vertical plane, said planes being close to and parallel with each other and said tubes of the two subdivisions alternating in arrangement with each other throughout the group, and a header provided with a series of four steam compartments arranged one in advance of the other and comprising two saturated steam compartments and two superheated steam compartments, said saturated and superheated steam compartments alternating in arrangement with each other from rear to front of the header, said compartments having rows of superheater tube end receiving openings arranged in at least two parallel transverse rows, each successive two tube openings in each transverse row constituting a working pair to receive the front and rear alined ends of a tube, one transverse row of tube end receiving openings connecting with the left hand tube ends of one tube group subdivision in one vertical row of flues and the other transverse row of tube end receiving openings connecting with the right hand tube ends of the other tube group subdivision in the same vertical row of flues.

In testimony whereof we affix our signatures.

COLUMBUS K. LASSITER.
